CIRCUIT BREAKER

Joseph D. Findley, Jr., Forest Hills, and Roswell C. Van Sickie, Wilkinsburg, Pa., assignors to Westinghouse Electric Corporation, East Pittsburgh, Pa., a corporation of Pennsylvania

Filed Dec. 20, 1956, Ser. No. 629,606

12 Claims. (Cl. 200—104)

This invention relates to circuit breakers and more particularly to high-speed electromagnet tripping devices for circuit breakers.

When a tractive electromagnet is used to trip a high-speed circuit breaker, the fastest possible build-up of useful pull in the magnet is desired. The initial rate of build-up of current and also pull is limited by the inductance of the coil. The inductance of the coil is determined by the total flux linkages with the turns of the coil. Some of the flux linkages are caused by useful flux crossing the working air gap of the magnet and threading the coil. The inductance due to the useful flux cannot be avoided if the magnet is to do useful work.

In most electromagnets there is a considerable portion of the total flux threading the coil or part of the coil which does not cross the working air gap. This so-called leakage flux does not contribute to the magnetic pull, but does cause inductance and thus reduces the rate of build-up of current and, therefore, of the magnet pull. It has been found that this leakage flux may be temporarily suppressed or delayed by placing a conductor of good conductivity, such, for instance, as copper in the path of the leakage flux. Eddy currents in the copper retard the build-up of the leakage flux and effectively reduce the inductance of the coil during the tripping period.

It is an object of the invention to provide a circuit breaker with an improved high-speed tripping electromagnet embodying novel shielding means for reducing the leakage flux to thereby reduce the inductance of the magnet coil during the working period.

Another object of the invention is to provide a circuit breaker with an improved high-speed tripping electromagnet having a fixed magnet yoke and an energizing coil embodying members of high conductivity disposed adjacent a considerable portion of the magnet yoke to reduce the inductance of the magnet and increase the rate of rise of useful flux in the air gap.

Another object of the invention is to provide a circuit breaker with an improved high-speed tripping electromagnet comprising a fixed magnet yoke and an energizing coil having shielding means of high conductivity disposed about the magnet yoke to reduce the leakage flux to thereby decrease the tripping time of the magnet.

Other objects and advantages of the invention will be pointed out in the following description and illustrated in the accompanying drawings, which disclose, by way of example, the principle of the invention and the best mode, which has been contemplated, of applying that principle.

In said drawings:

Fig. 1 is a vertical sectional view showing a circuit breaker operating mechanism embodying the principles of the invention;

Fig. 2 is a sectional view taken along line II—II of Fig. 1;

Fig. 3 is an elevational view of the tripping electromagnet and latching means;

2

Fig. 4 is a front elevational view of the tripping mechanism;

Fig. 5 is a sectional view through the tripping electromagnet taken on line V—V of Fig. 3; and

Fig. 6 is an exploded view of the tripping electromagnet.

The circuit breaker is of the type disclosed in the patent to Joseph D. Findley, Jr., Patent No. 2,866,031 entitled "Circuit Breaker," and assigned to the assignee of the instant invention.

The circuit breaker comprises generally a plurality of sets of separable contacts (not shown), an operating mechanism indicated generally at 23, a trip device indicated generally at 25 and a closing solenoid indicated generally at 27.

The moving contact structure for each pole of the breaker is connected by means of an operating rod 45 and nuts 49 to a cross bar 51 which is common to all poles of the breaker. The cross bar 51 is pivotally connected at its ends by pivot pins 53 (only one being shown) to an operating bell crank lever 55 which is pivotally mounted on a shaft 57 supported in the spaced side members 59 (only one being shown) of a generally U-shaped frame 61. The frame 61 is rigidly supported in the breaker frame structure (not shown) by means of a cross member 13 and a plate 62.

In addition to the operating bell crank lever 55, the operating mechanism consists of a closing lever 63 pivotally mounted on a shaft 65 supported in the side members 59 of the frame 61. The closing lever 63 is operatively connected by means of a link 67, to the moving armature 69 of the closing solenoid 27. The link 67 is connected by means of a pin 70 to the armature 69. The operating lever 55 and the closing lever 63 are connected by means of an underset toggle comprising toggle links 73 and 75 which are pivotally connected together by a knee pivot pin 77. The toggle link 73 is pivotally connected by a pin 79 to one arm of the operating bell crank lever 55 and the toggle link 75 is pivotally connected to the closing lever 63 by a pin 81 which also connects the link 67 to the closing lever. The closing lever 63 is held in the closed position by a spring biased latch 83 which normally engages a roller 85 on the pin 81.

The toggle 73, 75 is releasably held in a slightly underset position, in order to hold the breaker closed, by a latch member 87 which is pivoted on the shaft 65. A link 89 connects the knee 77 of the toggle 73, 75 to the latch member 87 being pivotally connected to the latter by a pin 91. The latch member 87 is normally releasably held in latching or holding positions by a balanced trigger latch 99 which is actuated to unlatching positions by operations of the trip device 25. A latch roller 93, rotatably mounted on the latch member 87 by a pin 95, normally engages the inner end 97 of the trigger latch 99 which is mounted for horizontal movement by pivot means 101 supported on a cross bar 103 which is, in turn, mounted on the cross member 13 by means of bolts 105, and by a bracket 107 secured to the under side of the cross bar 103.

The electromagnetic trip device 25 is supported on a front plate 109 secured to the cross bar 103 and to a cross member 15 by means of screws 111. The trip device comprises a fixed E-shaped laminated magnet yoke 113 (Figs. 3, 4, 5 and 6) rigidly supported between a top plate 115 and a bottom plate 117, both made of a highly conductive material, which are secured together by bolts 119 and nuts 121. The plates 115 and 117 are rigidly secured to the front of the front plate 109 by means of four bolts 123 (Fig. 1) which extend through openings in the front plate 109 and are threaded into tapped openings 125 (Fig. 6) in the top and bottom

plates 115 and 117. An energizing coil 126 surrounds the center leg of the fixed magnet yoke 113. A movable armature 127 is rigidly secured to the lower end of a U-shaped armature lever 129 (Figs. 1 and 4) the spaced side members of which are pivotally mounted on a pin 131 supported by and extending outwardly from the front plate 109, the outer end of the pin 131 being supported in a bracket 133 which is rigidly secured to the front plate 109. The lever 129 is spaced from the front plate 109 by a spacer 134. A member 135, secured to the upper end of the lever 129, carries an adjusting screw 136, which is adapted, upon energization of the electromagnet, to engage the outer end 100 of the latch 99 to actuate the latch. The latch 99 is biased by a spring 137 against an adjustable stop 139 (Fig. 2) supported on an upwardly extending portion 141 of the bracket 133 secured by screws 143 to the front plate 109. A spring 145 (Figs. 1 and 4), coiled about the pin 131, biases the armature member 135 against a stop 147 which is also supported by the portion 141 of the bracket 133.

When the electromagnet is energized in response to an overload current, it attracts the armature 127 and actuates the trigger latch 99 effecting release of the latch member 87. Upon release of the latch member 87, the toggle 73, 75 immediately collapses toward the left causing clockwise rotation of the operating bell crank lever 55 and opening of the breaker. The collapse of the toggle 73, 75 causes counterclockwise rotation of the toggle link 75 about the pin 81 during which rotation a projection 149 on the toggle link 75 engages and moves the latch 83 to its unlatching position. As soon as the latch 83 is disengaged from the roller 85, a spring 151, connected under tension between the armature 69 of the closing solenoid and the cross bar 103, moves the armature 69 toward the left to its unattracted position. This movement of the armature, through the link 67, rotates the closing lever 63 in a clockwise direction resetting the toggle 73, 75 and relatching the latch member 87 with the trigger latch 99. The leftward movement of the armature 69 is arrested by engagement of the link 67 with a fixed stop 153. The mechanism is now in condition to be closed by energization of the closing solenoid 27.

Energization of the closing solenoid 27 attracts the armature 69 toward the right which movement, through the link 67, rotates the closing lever 63 counterclockwise about its pivot 65. Since the latch member 87 is now held by the latch 99, the link 89 holds the toggle 73, 75 in thrust transmitting condition causing the toggle to transmit the force of the armature 69 to the operating bell crank lever 55 which thrusts the operating rod 45 upwardly to close the breaker. At the end of the closing stroke the latch 83 reengages the rollers 85 and holds the mechanism in the closed position.

An important feature of the invention is the construction and arrangement of the tripping electromagnet whereby the leakage flux is reduced which reduces the inductance of the energizing coil and increases the initial rate of rise of flux across the working air gap and with it, the rate of build-up of the pull of the magnet. It has been found that by placing pieces of a material of high conductivity, such, for instance, as copper in the path of unusable leakage flux, the eddy currents in the conductive material retard the build-up of the leakage flux and effectively reduce the initial inductance of the coil.

Referring to Figs. 3, 5 and 6, the electromagnet comprises, as previously described, the fixed E-shaped magnet yoke 113 rigidly held between the upper and lower plates 115 and 117 respectively by the bolts 119. The plates 115 and 117 are made of a material having high conductivity, such, for instance, as copper. Between the plates 115 and 117 respectively, and the magnet yoke 113 are disposed U-shaped pieces of insulation 155. A U-shaped strip 157 of insulation surrounds three edges of the magnet yoke and a U-shaped strip 159 of conduct-

ing material is disposed around the insulating strip 157 and between the latter and the bolts 119 as clearly seen in Figs. 3 and 5. Strips 161 of conducting material disposed one on each side of the coil 126 between the coil 126 and the outer legs of the magnet yoke, have their inner ends formed at right angles toward each other between the inner end of the coil and the magnet yoke. Insulating strips 163 of the same shape as the conducting strips 161 are disposed between the latter and the outer legs of the magnet yoke.

The facing sides of the plates 115 and 117 are recessed as at 165 to receive the coil 126 and the spool 167 on which it is wound. Spacers 169 of conducting material are placed in the grooves 165 between the inner end of the coil 126 and outer end of the plates 115 and 117, and are held in place by one of the bolts 119 which passes through openings in the plates 115 and 117 and in the spacers 169.

The plates 115 and 117 (Figs. 5 and 6) extend downwardly adjacent the sides of the armature 127 and the ends of the U-shaped conducting strip 159 extend downwardly adjacent the ends of the armature 127. This arrangement prevents the flux from flaring outward to the sides of the end pole faces and concentrates the flux directly across the air gaps thereby increasing the pull on the armature.

It will be seen that all of the surfaces of the magnet yoke, except the center leg of the magnet yoke and the three pole faces, have a conductive path adjacent them.

Tests on one embodiment of the invention have shown that the use of such conductive paths reduced the coil inductance from .024 henry to .017 henry. This reduced the time to reach 63% pull from .007 second to .005 second which reduced the tripping time .002 second or 29%.

The fast interrupting time provided by the invention will effect considerable reduction in wire damage in clearing faults on overhead lines, thereby permitting improved continuity of service and reduce line maintenance.

Having described the invention in accordance with the provisions of the patent statutes, it is to be understood that various changes and modifications may be made in the structural details and in the arrangement of parts without departing from the spirit of the invention.

We claim as our invention:

1. An electromagnetic trip device for a circuit breaker comprising a magnet yoke, a pair of spaced rigid members of highly conductive material disposed on opposite sides of said magnet yoke, energizing means on said magnet yoke, and a plurality of conducting members of highly conductive material disposed adjacent the edge portions of said magnet yoke to reduce the leakage flux of said magnet yoke and thereby increase the rate of build-up of useful flux.
2. An electromagnetic trip device for a circuit breaker comprising a laminated magnet yoke, a pair of spaced rigid members of a highly conductive material between which said laminated magnet yoke is disposed, a U-shaped strip of a highly conductive material disposed adjacent three edges of said laminated magnet yoke to reduce the leakage flux of said magnet yoke.
3. An electromagnetic trip device for a circuit breaker comprising a magnet yoke, a pair of rigid members of highly conductive material supporting said magnet yoke between them, members of insulating material disposed between said rigid members and said magnet yoke, a plurality of conducting members of a highly conductive material disposed adjacent the edge portions of said magnet yoke to reduce the leakage flux of said magnet yoke, and insulating means between said plurality of conducting members and said magnet yoke.
4. An electromagnetic trip device for a circuit breaker comprising an E-shaped magnet yoke, a pair of rigid members of a highly conductive material having said E-shaped magnet yoke disposed between them, an energizing coil

mounted on the center leg of said magnet yoke, and conducting strips of a highly conductive material adjacent the edge portions of said magnet yoke, said rigid members and said conductive strips reducing the leakage flux of said magnet yoke.

5. An electromagnetic trip device for a circuit breaker comprising a laminated E-shaped magnet yoke, a pair of relatively thick plates of a highly conductive material disposed one on each side of said magnet yoke, an energizing coil mounted on one of the legs of said E-shaped magnet yoke, and conducting strips of a highly conductive material disposed adjacent portions of the edges of said laminated magnet yoke, said plates and said conducting strips reducing the leakage flux of said magnet yoke.

6. An electroresponsive device comprising a rectangular E-shaped magnet yoke, a pair of plates of a highly conductive material disposed on opposite sides of said magnet yoke, said plates being larger than said magnet yoke, securing means securing said plates together to support said magnet yoke, an energizing coil mounted on the center leg of said magnet yoke, said plates being recessed to receive said energizing coil, and a U-shaped conducting strip of a highly conductive material disposed around three sides of said magnet yoke between said magnet yoke and said securing means, said plates and said conducting strip reducing the leakage flux of said magnet yoke.

7. An electroresponsive device comprising an E-shaped laminated magnet yoke having three pole faces, a pair of plates of a highly conductive material disposed on opposite faces of said laminated magnet yoke and secured together to mount said magnet yoke, an energizing coil surrounding the middle leg of said magnet yoke, a U-shaped conducting strip of a highly conductive material surrounding the edges of said magnet yoke except the pole faces, conducting strips of a highly conductive material disposed between said coil and the inner edges of the outer legs of said magnet yoke, said plates and said conducting strips reducing the leakage flux of said magnet yoke.

8. An electroresponsive device comprising an E-shaped laminated magnet yoke having three pole faces, a pair of plates of a highly conductive material disposed on opposite faces of said laminated magnet yoke and secured together to mount said magnet yoke, members of insulating material between said plates and said magnet yoke, an energizing coil surrounding the middle leg of said magnet yoke, a U-shaped conducting strip of a highly conductive material surrounding the edges of said magnet yoke except the pole faces, conducting strips of a highly conductive material disposed between said coil and the inner edges of the outer legs of said magnet yoke, insulating means between each of said conducting strips and said magnet yoke, said plates and said conducting strips reducing the leakage flux of said magnet yoke.

9. A tractive electroresponsive device comprising a magnet yoke, a pair of members of a highly conductive non-magnetic material disposed on opposite sides of said magnet yoke, and means of a highly conductive non-magnetic material disposed adjacent the edge portions of said magnet yoke, insulating means disposed between said highly conductive non-magnetic materials and said magnetic yoke, said insulating means being substantially thin to enable said highly conductive non-magnetic materials to be positioned in close enough proximity to said magnet yoke to effectively reduce the leakage flux and thereby increase the rate of build-up of useful flux.

10. A tractive electroresponsive device comprising a fixed magnet yoke and a movable armature, an energizing coil on said magnet yoke, and shielding means of a highly conductive non-magnetic material surrounding said magnet yoke except the portion adjacent said armature, said shielding means being in close enough proximity to said magnet yoke to effectively reduce the leakage flux in said magnet yoke to thereby increase the rate of build-up of useful flux.

11. A tractive electromagnetic device comprising a magnet yoke having a plurality of pole faces, a movable armature providing a plurality of air gaps, an energizing coil on said magnet yoke, a shield of a highly conductive material surrounding said electromagnet except the portion thereof adjacent said armature, said shield being disposed proximate to said magnet yoke to reduce the leakage flux in said magnet yoke to thereby increase the rate of build-up of useful flux across said air gaps, and portions of said shield extending adjacent the ends of said armature to effect a concentration of flux at said pole faces.

12. A tractive electromagnet comprising a magnet yoke having a plurality of pole faces, a movable armature disposed adjacent said pole faces providing a plurality of air gaps, an energizing coil on said magnet yoke, shielding means comprising a pair of members of a highly conductive material disposed at opposite sides of said magnet yoke, a shield of a highly conductive material surrounding the edges of said magnet yoke proximate thereto except the pole faces, said shielding means and said shield reducing the leakage flux to thereby increase the build-up of useful flux across said air gaps, and the end portions of said shield extending beyond said pole faces and adjacent the ends of said armature to effect concentration of flux at said pole faces.
